US0D1074691S

(12) **United States Design Patent** (10) **Patent No.:** **US D1,074,691 S**
Berkowitz et al. (45) **Date of Patent:** **** May 13, 2025**

(54) **DISPLAY SCREEN WITH A GRAPHICAL USER INTERFACE**

(71) Applicant: **ADP, Inc.**, Roseland, NJ (US)

(72) Inventors: **Jack Berkowitz**, Mendham, NJ (US); **Amin Venjara**, Livingston, NJ (US); **Zafrir Babin**, Glen Rock, NJ (US); **Brent Weiss**, Princeton, NJ (US); **Justo Pastor**, Fairfield, NJ (US); **Malvika Tiwari**, Montclair, NJ (US); **Cory Schamble**, Hackettstown, NJ (US); **Hafeez Raji**, Huntingdon Station, NY (US); **Mathew Skaria**, East Hanover, NJ (US); **Sreenath Kodedala**, Budd Lake, NJ (US); **Szabi Nagy**, Gladstone, NJ (US); **Anuj Singh**, Wayne, NJ (US); **Kishore Bangali**, Mt. Arlington, NJ (US); **Rajan Patel**, Avenel, NJ (US); **Siva Bangaru**, Hyderabad (IN); **Manoj Oleti**, Hyderabad (IN); **Nakul Kapoor**, New Providence, NJ (US); **Zeeshan Anwar**, Monroe, NJ (US); **Mark Anthony Maraj**, Jersey City, NJ (US); **Vibhor Shukla**, Livingston, NJ (US); **Michael Ratcliff**, West Caldwell, NJ (US); **Leon Liu**, Livingston, NJ (US); **Anil Dhotre**, Parsippany, NJ (US); **Annette Allen**, Linden, NJ (US); **WaiWah Pak**, Livingston, NJ (US); **Pallavi Renati**, Hyderabad (IN); **Praveen Kumar Kommineni**, Hyderabad (IN)

(73) Assignee: **ADP, Inc.**, Roseland, NJ (US)

(**) Term: **15 Years**

(21) Appl. No.: **29/789,115**

(22) Filed: **Sep. 1, 2021**

(30) **Foreign Application Priority Data**

May 29, 2021 (IN) 344015-001

(51) **LOC (15) Cl.** **14-04**

(57) **CLAIM**

The ornamental design for a display screen with a graphical user interface, as shown and described.

DESCRIPTION

The sole FIGURE is a view of a display screen with a graphical user interface.

The outermost broken lines in the drawings show the display screen and form no part of the claimed design. The remaining broken lines show portions of the graphical user interface and form no part of the claimed design.
